Primary Examiner — Richard Edgar*Assistant Examiner* — Jessica Ruth Grable(74) *Attorney, Agent, or Firm* — Fish & Richardson P.C.(57) **CLAIM**

The ornamental design for a sheep planter, as shown and described.

DESCRIPTION

FIG. 1 is a front, top, right perspective view for a sheep planter, showing the new design;

FIG. 2 is a front, bottom, left perspective view thereof;

FIG. 3 is a front elevation view thereof;

FIG. 4 is a rear elevation view thereof;

FIG. 5 is a left side view thereof;

FIG. 6 is a right side view thereof;

FIG. 7 is a top plan view thereof; and,

FIG. 8 is a bottom plan view thereof.

The broken lines of even length shown in the drawings illustrate portions of the component of the sheep planter that form no part of the claimed design.

1 Claim, 8 Drawing Sheets(56)
